HARVY TULLIS, OF LISBON, OHIO.

SAFETY GAS CUT-OFF.

942,601.

Specification of Letters Patent. Patented Dec. 7, 1909.

Application filed May 19, 1909. Serial No. 496,929.

To all whom it may concern:

Be it known that I, HARVY TULLIS, a citizen of the United States, and resident of Lisbon, in the county of Columbiana and 5 State of Ohio, have invented a certain new and useful Safety Gas Cut-Off, of which the following is a full, clear, and exact description.

The object which the present invention 10 has principally in view is to provide a mechanism for cutting off the supply of gas in the event of the same being inadvertently or otherwise temporarily suspended.

One embodiment of the invention is dis- 15 closed in the structure illustrated in the accompanying drawings wherein like characters of reference indicate corresponding parts in all the views.

Figure 1 is a side elevation of a gas pipe 20 having attached thereto a cut-off constructed in accordance with the present invention; Fig. 2 is an end elevation of the same; Fig. 3 is a vertical longitudinal section of the same, showing the valve in its open position; Fig. 4 is a cross section of the same taken on the line 4—4 in Fig. 3; and Fig. 5 is a vertical longitudinal section of the cut-off, the valve being shown in its closed position.

A great deal of disaster and discomfort 30 has been experienced in the past, due to the accidental or intentional suspension of gas service in buildings, and the renewal of the same after the light has become extinguished, due to the suspension. Many cases of asphyxiation have been traced to this cause, as where a person on retiring has left a gas light burning, which through 35 accidental suspension of service has become extinguished, as a light, while the pipe remains open to permit the gas to flow unburned into the chamber when the pressure is again renewed. It is to avoid this action 40 that I have provided the present invention, which consists in interposing between the pipe sections 6 and 7, a device having a body portion 8, in which is formed a chamber 9, of enlarged area to permit the movement of a valve 10 to and from its seat 11. 45 The valve 10 is fixedly attached to a valve rod 12, which is guidably supported in a perforation formed in the end of an upright guide rod 13. The guide rod 13 may 50 be substituted by a spider casting suitably secured in the body 8. The rod 12 is supported at the end opposite that which is

mounted in the guide 13, by being pivotally connected with a rocking lever 14, pivoted in the body portion 8 at 15. The said lever when in the position shown in Fig. 3 of the 60 drawings, holds the valve 10 in the position shown in said view, or raised from the seat 11. When, however, the lever is moved to the position shown in Fig. 5 of the drawings, the valve 10 is moved against the seat 65 11. The cut-off is placed between the pipes 6 and 7 in such manner that the valve 10 is interposed between the source of gas and the seat 11, the gas flowing in the direction shown by arrows in the drawings. The 70 free end of the lever 14 is connected by means of a connecting rod 16, to a bell-shaped member 17, mounted to inclose a small pipe 18, at the top of which there is secured a washer 19, which prevents the es- 75 cape of gas from the interior of the bell-shaped member 17. The bell-shaped mem- 80 ber 17 is increased or decreased in weight by the use of rings 20 of various weights, which are screwed upon the lower end of the bell-shaped member 17. The rod 16 is secured to the upper end of the bell-shaped member 17 by a connecting link 21.

With a device constructed as shown in the drawings and as herein described the operation is as follows: When the device is inserted in the system between the pipes 6 and 7, the pressure of the gas operates to set the valve 10 on the seat 11. When both sections 6 and 7 of the pipe are secured to the device, the bell-shaped member 17 is raised by hand, removing the valve 10 from the seat 11. It is now calculated that the gas pressure which is permitted to enter through the pipe 18 into the upper part of the bell-shaped mem- 85 ber 17, will suspend the said bell-shaped in- 90 member in the position shown in Fig. 3 of the drawings. The member 17 continues to stand in the position shown, until through accident or otherwise the pressure of the gas 95 in the pipes 6 and 7 falls below that pres- 100 sure which is sufficient to sustain the bell-shaped member 17. Whenever this happens, the member 17 falls to the position shown in Fig. 5, throwing the lever 14 to the position 105 shown, and closing the valve 10 upon the valve seat 11. These parts are delicate in operation, and care is taken to provide against the corroding or adhesion of the parts, so that the action described is cer- 110 tain and requires little or no force. When the valve 10 is seated, any subsequent re-

newal or increase of pressure on the service side in the pipes, only operates to more firmly seat the valve by pressing against the back thereof. This absolutely closes the pipe 5 against the admission of gas beyond the valve.

The cut-off herein described is usually placed in the pipe system at or near the meter or between the service and the burners. When it is desired to renew the service, it is necessary to manually raise the member 10, thereby removing the valve 10 from its seat and reestablishing the pressure throughout the pipes and on both sides of the 15 valve 10.

While I have herein described this system as applicable to what is known as gas lighting, and as more applicable to municipal systems for the supply of the same, it will be 20 understood that the cut-off is applicable to use in gas supply systems wherein is used gasoline, or privately carbureted gas.

Having thus described my invention, I

claim as new and desire to secure by Letters Patent:

A safety gas cut-off, comprising a straight pipe section having a valve mounted to operate longitudinally therein, a rocking lever mounted in said section adapted to open and close the said valve, a vertical pipe extension 30 opening into the said pipe section on the delivery side of the said valve and forming an open communication from said section, an inverted closed end tube guidably mounted on said vertical extension and 35 forming a gas tight sliding joint therewith, and a connection between said rocking lever and said tube to open and close the said valve.

In testimony whereof I have signed my 40 name to this specification in the presence of two subscribing witnesses.

HARVY TULLIS.
